United States Patent Office

Des. 197,509
Patented Feb. 18, 1964

197,509

MOTOR VEHICLE

David R. Dodd, 5503 Pat Lane, Richmond, Va.

Filed Oct. 5, 1961, Ser. No. 66,981

Term of patent 14 years

(Cl. D14—3)

FIG. 1

FIG. 2

FIG. 3

FIG. 4

FIG. 1 is a front perspective view of a motor vehicle showing my new design;

FIG. 2 is a rear perspective view thereof;

FIG. 3 is an elevational view of the side opposite that shown in FIG. 1; and

FIG. 4 is a perspective view showing the motor vehicle in collapsed position.

I claim:

The ornamental design for a motor vehicle, as shown.
